ADJUSTABLE-HEAD ELECTRONIC FLASH UNIT

Claus Prochnow, Braunschweig, Klaus Pfitzner, Linden,
and Jochen Kramer and Hans Schönfeld, Wolfsburg,
Germany, assignors to Rollei-Werke Franke &
Heidecke, Braunschweig, Germany

Filed July 16, 1973, Ser. No. 379,558

Claims priority, application Germany Jan. 18, 1973

Term of patent 14 years

Int. Cl. D16—05

U.S. Cl. D61—1 F

FIG. 3

FIG. 2

FIG. 1

FIG. 4

FIG. 6

FIG. 5

FIG. 1 is a front elevational view of an adjustable-head electronic flash unit showing our new design;

FIG. 2 is a right side elevational view thereof;

FIG. 3 is a top plan view thereof;

FIG. 4 is a rear elevational view thereof;

FIG. 5 is a bottom plan view thereof;

FIG. 6 is a left side elevational view thereof with the lamp head shown in upwardly adjusted position.

I claim:

The ornamental design for an adjustable-head electronic flash unit, substantially as shown and described.
